UNITED STATES PATENT OFFICE.

MARTIN L. BUSH, OF LAWRENCE, MASSACHUSETTS.

GEARING FOR VALVE-GRINDERS.

1,175,123.

Specification of Letters Patent. Patented Mar. 14, 1916.

Application filed July 28, 1915. Serial No. 42,391.

To all whom it may concern:

Be it known that I, MARTIN L. BUSH, a citizen of the United States, residing at Lawrence, in the county of Essex and State of Massachusetts, have invented a new and useful Gearing for Valve-Grinders, of which the following is a specification.

This invention relates to a tool especially designed for grinding valve seats and valves, one of the objects of the invention being to provide a device of this type which can be used not only for the purpose stated but also as a brace for operating bits or drills.

A further object is to provide a structure of this character adapted, when operated, to rotate the engaged valve in opposite directions successively or to rotate the valve engaging stem continuously in one direction only.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a vertical transverse section through the device. Fig. 2 is a section on line A—B Fig. 1.

Referring to the figures by characters of reference 1 designates the body of the tool, the same being preferably a single casting forming a frame in the lower portion of which is provided a central opening 2 for the reception of a tubular guide or holding member 3. A set screw 3' is provided for engaging this holding member to secure it against movement within the body. Extending laterally from the body 1 is a stud 4 on which a wheel 5 is mounted for rotation, this wheel being detachably secured on the stud in any suitable manner and being reversible. One side of the wheel is provided with a mutilated gear 6, while the other side has a continuous gear 7. Either of these gears is adapted to mesh with oppositely disposed bevel gears 8 and 9 located at the ends of guide 3 and mounted on a stem 10 which is adapted to rotate within the guide 3. Each of the gears is secured to the stem or

spindle 10 by means of a set screw 11. A handle 12 is adapted to be detachably secured to either side of the wheel 5 and another handle 13 is detachably secured to the top of the frame 1. A third handle 14 extends laterally from the body 1 and in alignment with the stud 4, said handle 14 and stud 4, however, being located at opposite sides of the body. The stem or spindle 10 is adapted to engage the valve to be ground or, if preferred, can be provided with a chuck for holding a bit or the like.

When the device is to be used for grinding a valve the mutilated gear 6 is placed inwardly so as to engage the two gears 8 and 9. After the stem or spindle 10 has been placed in engagement with the valve, the wheel 5 can be rotated and, consequently, the mutilated gear will first rotate gear 8 in one direction and then rotate gear 9 in the opposite direction so that stem or spindle 10 will thus be correspondingly rotated back and forth, thereby producing a better grinding action than is possible where the valve is rotated continuously in one direction. However, should it be desired to rotate the valve continuously in one direction, it would merely be necessary to reverse the wheel 5 so as to bring the gear 7 into mesh with the two gears 8 and 9. By then loosening one of the set screws 11, so as to release its gear 8 or 9 from the stem or spindle 10, the wheel 5 can be rotated and motion will be transmitted through gear 7 and one of the gears 8 or 9 to the spindle 10. This last arrangement is preferably used where the tool is employed for rotating a bit or drill.

The gears 8 and 9 differ as to the number of teeth thereon with the result that during the actuation of the tool, for the purpose of grinding a valve, the valve will be moved forwardly a greater distance than it is moved backwardly with the result that it will not be brought back to its original position on the seat as has been the case heretofore where mechanism has been employed for oscillating valves and grinding them.

The wheel 5 is preferably provided with a small central gear 14 and by shifting the body 1 longitudinally of the stem or spindle 10, one of the gears on said stem can be brought into mesh with this gear 14. Thus it is possible to use the tool as a two speed breast drill.

What is claimed is:—

1. A tool of the class described including

a body, a longitudinally adjustable tubular member therein, a spindle mounted for rotation in said member, gears detachably secured to the spindle and adjacent the ends 5 of the tubular member, and a reversible wheel journaled on the body, said wheel being provided on one side with a mutilated gear and on its other side with a continuous gear, and means for rotating the wheel.

10 2. A tool of the class described including a body, a tubular member adjustable longitudinally therein, a spindle mounted for rotation in said member, gears detachably secured to the spindle and adjacent the ends 15 of the tubular member, a stud extending

from the body, a wheel mounted for rotation on the stud, means for rotating the wheel, said wheel having a mutilated gear on one side and a continuous gear on the opposite side, either of said gears being 20 adapted to engage the gears upon the spindle.

In testimony that I claim the foregoing as my own, I have hereto affixed my signature in the presence of two witnesses.

MARTIN L. BUSH.
